UNITED STATES PATENT OFFICE

142,043

DESIGN FOR A DRAWER PULL OR SIMILAR ARTICLE

Roy A. Stone, Rockford, Ill., assignor to National Lock Company, Rockford, Ill., a corporation of Delaware

Application December 4, 1944, Serial No. 116,694

Term of patent 7 years

(Cl. D10—8)

To all whom it may concern:

Be it known that I, Roy A. Stone, a citizen of the United States, residing at Rockford, in the county of Winnebago and State of Illinois, have invented a new, original, and ornamental Design for Drawer Pull or Similar Article, of which the following is a specification, reference being had to the accompanying drawing, forming part thereof.

In the drawing,

Fig. 1 is a side elevation of a drawer pull or similar article embodying my new design;

Fig. 2 is a front elevation thereof;

Fig. 3 is an end elevation thereof; and

Fig. 4 is a sectional view on the line 4—4 of Fig. 1.

I claim:

The ornamental design for a drawer pull or similar article, substantially as shown.

ROY A. STONE.
